Inventor
Joseph L. Pearson
by R. A. Lacey, Atty:

UNITED STATES PATENT OFFICE.

JOSEPH LAZARUS PEARSON, OF GOLDSBOROUGH, NORTH CAROLINA.

DESIGN FOR A PIPE-WRENCH.

SPECIFICATION forming part of Design No. 27,211, dated June 15, 1897.

Application filed April 26, 1897. Serial No. 634,048. Term of patent 7 years.

To all whom it may concern:

Be it known that I, JOSEPH LAZARUS PEARSON, a citizen of the United States, residing at Goldsborough, in the county of Wayne and State of North Carolina, have invented and produced a new and original Design for Pipe-Wrenches; and I do hereby declare the following to be a full, clear, and exact description of the same, reference being had to the accompanying drawings, forming a part thereof.

My invention has relation to a new and original design for a pipe-wrench.

It relates to the entire configuration of the wrench and especially to a wrench made of a single piece of steel.

My invention relates particularly to the design for a pipe-wrench, as illustrated in the accompanying drawings, in which—

Figure 1 is a perspective view of a pipe-wrench embodying my design. Fig. 2 is a transverse section on the line 2 2 of Fig. 1. Fig. 3 is a transverse section on the line 3 3 of Fig. 1. Fig. 4 is a transverse section on the line 4 4 of Fig. 1.

The leading features of my design appear in the following description.

1 is the handle of a wrench, and it is provided with a hand-grip 2, terminating in a screw-driver point 3. The handle proper is

formed with parallel plane sides 4 and 5, a 30 semicircular back edge 6, and a convex front edge 7, which is provided with a series of longitudinal parallel serrations 8.

9 represents the integral jaw extending rearwardly from the head 10 and at acute 35 angle to the handle. The inner face of said jaw is provided with a series of transverse parallel ratchet-shaped teeth 11.

12 represents a cylindrical hammer-face 40 projecting rearwardly from the wrench.

The tool will be found very handy and convenient in all branches of the mechanical trades as well as for general farm and household use, and may be nickel-plated or not to suit the wants of the trade.

Having thus fully described my invention, what I claim as new and useful, and desire to secure by Letters Patent of the United States, is—

The design for a pipe-wrench, substantially 30 as herein shown and described.

In testimony whereof I affix my signature in presence of two witnesses.

JOSEPH LAZARUS PEARSON.
